Atty's.

UNITED STATES PATENT OFFICE.

KENNETH HOWIE, OF NORRISTOWN, PENNSYLVANIA, ASSIGNOR TO WILDMAN MFG. CO., OF NORRISTOWN, PENNSYLVANIA, A CORPORATION OF PENNSYLVANIA.

KNITTING IMPLEMENT FOR KNITTING MACHINES.

Application filed May 21, 1927. Serial No. 193,281.

The invention concerns a composite knitting implement, i. e., one built up of a plurality of members to present a comparatively thin forward portion to work between 5 and in immediate association with the needles and a shank or stem portion which is built up by the addition of a member or members to the stem portion of the member first mentioned, said built up stem portion being of a thickness to run in the groove or slot of the bed of the machine.

I have shown the invention in connection with a combined sinker and web holder, though I do not limit myself in this respect.

15 In the drawings:

Figure 1 is a side view of a sinker and web holder combined embodying the invention.

20 Fig. 2 is a plan view of Fig. 1.

Fig. 3 is a perspective view of the reinforcing member, to be applied to the stem and butt of the main element.

Fig. 4 is a sectional view of Fig. 3.

25 Fig. 5 is a perspective view of the main element of the composite elements, to go with the parts shown in Figs. 1 to 4, or with the parts shown in Figs. 6 and 7.

Fig. 6 is a view of the auxiliary shank and butt member belonging to the form of 30 the invention shown in Figs. 5 to 8 inclusive.

Fig. 7 is a perspective view of a butt cap member.

35 Fig. 8 is a sectional view of the composite implement made up of the parts shown in Figs. 5, 6 and 7.

Referring to Figs. 1 and 2, *a* indicates the main member of the implement and for the purpose of disclosing the nature of my invention I have illustrated it as carried out 40 in connection with a combined web holder and sinker.

This member is stamped in one piece from thin tempered sheet metal with the forward 45 or head portion *a*, a stem portion *a*¹ and a butt *a*². The stem portion is to run in the groove or slot of the bed or carrier of the machine and the butt is to enter the groove of the cam member of the machine.

50 Combined with the stem and butt portions of the implement is the auxiliary or reinforcing member composed of a stem portion *b* and a butt portion *c*. This member is made of thin sheet metal which may be 55 stamped out and then formed by dies to pro-

vide the butt portion *c* having flanges *c*¹ spaced apart from the main wall *c* a distance equal to the thickness of the butt portions *a*² of the main member, so that the auxiliary member may be joined to the main member by slipping the hollow butt member *c* onto the butt *a*² of the main member *a*.

This auxiliary member is made from soft stock and then tempered, and as above, 65 stated, the main member *a* is stamped out of tempered stock.

Referring to Figs. 5, 6, 7 and 8, the auxiliary or reinforcing member *d* with its butt portion *d*¹ is stamped out of thin tempered 70 stock of the form and size suitable to lay alongside of the stem portion *a*¹ and butt *a*² of the main member *a*, being similar in this respect to the form first described in so far as the stem portion is concerned.

In this second form shown in Figs. 5 to 8 the auxiliary member is held to the main member by a hollow cap piece *e*. This is made from soft stock drawn into the inverted cup shape shown and then tempered. 84 It is of a size to fit closely over the two butt portions *a*² and *d*¹. This cap may be pressed down over these butt portions to be maintained thereon by its tight fit alone.

It will be understood that the main member of the composite implement is of the form shown in Fig. 5, and this is combined either with the form of auxiliary member shown in Fig. 3, or with the auxiliary members shown in Figs. 6 and 7, to make up the 90 complete implement.

It will be understood that with my improvement accuracy in construction can be secured and particularly as between the stem and nose portion of the implement. It 95 has been the practice to form the implement in one piece with its forward or nose portion of reduced thickness and then the implement would be tempered, but this is objectionable because of the liability for warping 100 to take place.

It will be noted that in both forms of the implement the butts of the main and auxiliary members lie side by side and in contact and that these butt portions are held 105 together. In the first form the means for holding the butts together consist of the flanges *c*¹, *c*² integral with the butt *c*, while in the second form the holding means consists of the independent cap *e*. 110

In both instances the butt a^2 of the main member is thus reinforced by means embracing it; in Fig. 3 by the flanges C' bent around its edges and in Figs. 7 and 8 by the cap member. Thus the holding means in itself presents edge wear surfaces.

I claim:

1. A composite knitting implement for knitting machines having a main member provided with a forward or nose portion to work between the needles, and an integral stem portion provided with a butt, and an auxiliary member having a stem and butt portion to lie alongside the stem and butt portion of the main member and means for holding the butt portions of the said members together, said means presenting wear surfaces, substantially as described.
2. A composite knitting implement for knitting machines according to claim 1, in which the means for holding the auxiliary and main members together consists of a cap member fitting over the butts of said members.
3. A composite knitting implement for knitting machines having a reduced forward end to work between the needles and a thicker stem and butt portion, consisting of a main member stamped from tempered thin stock, and having a forward portion and a stem and butt of one thickness, and an auxiliary member having a stem and butt portion to lie alongside of the stem and butt portion of the main member, with embracing means holding the butts together.
4. A composite knitting implement ac-

cording to claim 3 in which the embracing means is formed from soft stock and then tempered.

5. A composite knitting implement for knitting machines having a main member provided with a forward or nose portion to work between the needles, and an integral stem portion provided with a butt, and an auxiliary member having a stem and butt portion to lie alongside the stem and butt portion of the main member and means for holding the butt portions of the said members together, said means presenting edge wear surfaces.

6. A composite knitting implement for knitting machines having a main member provided with a forward or nose portion to work between the needles, and an integral stem portion provided with a butt, and an auxiliary member having a stem and butt portion to lie alongside the stem and butt portion of the main member, with embracing means to hold the butts together.

7. A composite knitting implement for knitting machines having a main member provided with a forward or nose portion to work between the needles, and an integral stem portion provided with a butt, and an auxiliary member having a stem and butt portion to lie alongside the stem and butt portion of the main member, and means embracing said butts to hold them together.

In testimony whereof, I affix my signature.

KENNETH HOWIE.
